[57] CLAIM

The ornamental design for wrapping head for round ice cream sandwich forming and wrapping machine, as shown and described.

DESCRIPTION

FIG. 1 is a front perspective view, viewed from above, of a wrapping head for a round ice cream sandwich forming and wrapping machine, showing my new design;

FIG. 2 is a rear perspective view thereof, viewed from below;

FIG. 3 is a top plan view thereof;

FIG. 4 is a front elevational view thereof;

FIG. 5 is a side elevational view thereof, viewed from the left of FIG. 4;

FIG. 6 is a side elevational view thereof, viewed from the right of FIG. 4; and

FIG. 7 is a bottom plan view thereof.
